UNITED STATES PATENT OFFICE.

HOMER A. CURTISS, OF MERIDEN, CONNECTICUT.

DESIGN FOR A FERRULE.

SPECIFICATION forming part of Design No. 23,344, dated June 12, 1894.

Application filed April 20, 1894. Serial No. 508,383. Term of patent 3½ years.

To all whom it may concern:

Be it known that I, HOMER A. CURTISS, a citizen of the United States, residing at Meriden, county of New Haven, and State of Connecticut, have invented and produced a new and original Design for Ferrules, of which the following is a specification, reference being had to the accompanying drawing, forming part thereof, and showing my newly-designed ferrule in side view.

The leading feature of my design consists of a raised ornamental scroll-work or roccoco border partly surrounding a plain or unornamented space on each side of the ferrule.

15 In the drawing *a* denotes the plain space

and *b* the raised ornamental scroll-work or roccoco border partly surrounding said plain space *a* so as to inclose it below and on both sides.

The ferrule is shaped to form raised rings 20 or beads *c* above and below the raised roccoco or scroll-work.

I claim—

The design for a ferrule substantially as shown and described.

HOMER A. CURTISS.
